Primary Examiner — Eric L Goodman*Assistant Examiner* — Darcey E Heflin(74) *Attorney, Agent, or Firm* — Alexander S. Anoff;
Amanda Herman(57) **CLAIM**

The ornamental design for a dietary supplement package with surface ornamentation, as shown and described.

DESCRIPTION

FIG. 1 is a perspective view of a dietary supplement package with surface ornamentation showing a new design;

FIG. 2 is a front view of the new design;

FIG. 3 is a right side view of the new design;

FIG. 4 is a rear view of the new design;

FIG. 5 is a left side view of the new design;

FIG. 6 is a top view of the new design; and,

FIG. 7 is a bottom view of the new design.

Dashed lines represent environmental context and form no part of the claimed design.

1 Claim, 4 Drawing Sheets(56)
